UNITED STATES PATENT OFFICE.

GEORGE C. BOLES, OF PEEBLES, OHIO.

RAIL-JOINT.

1,242,133.

Specification of Letters Patent.

Patented Oct. 9, 1917.

Application filed April 28, 1917. Serial No. 165,260.

To all whom it may concern:

Be it known that I, GEORGE C. BOLES, citizen of the United States, residing at Peebles, in the county of Adams and State 5 of Ohio, have invented certain new and useful Improvements in Rail-Joints, of which the following is a specification, reference being had to the accompanying drawings.

This invention relates to certain improvements 10 in rail joints, and has relation more particularly to a device of the general character of a chair type, and it is an object of the invention to provide a rail joint having novel and improved means for effectively 15 maintaining the meeting ends of rails in assembled relation and whereby the possibility of "pounding" is substantially entirely eliminated when rolling stock passes thereover.

20 This invention consists in the details of construction and in the combination and arrangement of the several parts of my improved rail joint, whereby certain important advantages are attained and the device is 25 rendered simpler, less expensive and otherwise more convenient and advantageous for use, as will be hereinafter more fully set forth.

The novel features of the invention will 30 hereinafter be definitely claimed.

In order that my invention may be the better understood I will now proceed to describe the same with reference to the accompanying drawing, wherein—

35 Figure 1 is a view in side elevation, of a rail joint constructed in accordance with the embodiment of my invention;

Fig. 2 is a view in elevation of a plate as herein embodied, detached;

40 Fig. 3 is a sectional view taken substantially on the line 3—3 of Fig. 1; and

Fig. 4 is a transverse sectional view of the chair as herein embodied, and showing in detail a groove formed in the inner face 45 of one of the blocks or flanges of the chair.

As disclosed in the accompanying drawing, the meeting ends of the rails R are adapted to be rested upon the chair C. The upper surface of the chair C is provided 50 with a groove or channel 1 extending entirely thereacross and which is adapted to snugly receive the meeting ends R. The opposite end portions of the chair are defined by the upstanding flanges or blocks 2 having their inner or opposed faces cut 55 away to produce the wedge grooves or chan-

nels 3. The upper walls 4 of the grooves or channels 3 are disposed on predetermined longitudinal inclines, the inclination of one of said upper walls 4 being reversed to the 60 inclination of the upper wall 4 of the second groove or channel 3.

Co-acting with the opposite sides of the meeting ends R of the rails are the plates P, said plates being of such a width as to 65 snugly fit between the heads and flanges of the rail. The outer face of each of the plates P is provided with an outstanding elongated block 5, provided entirely therealong with the groove or channel 6. The 70 lower flange 7 afforded by said groove 6 is of wedge formation and is adapted to coact, in a manner which is believed to be entirely apparent to those skilled in the art to which my invention appertains, with a 75 groove or channel 3 produced in the inner face of one of the flanges or blocks 2. The upper flange 8 afforded by the groove or channel 6 overlies the top of the co-acting flange or block 2, and said flange 8 is provided with openings 9 adapted to register with the recesses 10 produced in the upper surface of said flange or block 2. The 80 openings 9 are threaded for co-action with the threaded portions 11 of the shanks of 85 the bolts 12. The free end portions of the shanks of the bolts are smooth, as indicated at 14, and are adapted to freely extend within the recesses 10, whereby, it will be 90 perceived, the plates P may be effectively held in assembled relation.

It will also be self-evident that in applying or removing the plates P, the same must be forced in opposite directions so that in removing a single plate no displacement of the second plate is effected.

From the foregoing description it is thought to be obvious that a rail joint constructed in accordance with my invention is of a simple and comparatively inexpensive nature, and is well adapted for use by reason of the convenience and facility with which it may be assembled; and it will also be obvious that my invention is susceptible of some change and modification without material departure from the principles and spirit thereof, and for this reason I do not wish to be understood as limiting myself to the precise arrangement and formation of the several parts herein shown, in carrying out my invention in practice, except as hereinafter claimed.

Having thus fully described my invention, what I desire to claim and secure by Letters-Patent is:

1. In combination with the meeting ends 5 of rails, a chair upon which said meeting ends are adapted to rest, the opposite end portions of said chair being provided with upstanding blocks, the opposed faces of the blocks being provided with channels, the 10 upper walls of said channels being longitudinally inclined, the inclination of one of said upper walls being reversed to the inclination of the upper wall of the second channel, and plates arranged at opposite sides of 15 the meeting ends of the rails; each of said plates being provided with an outstanding block provided with a channel affording separated flanges, the upper flange of the block being adapted to overlie a 20 block of the chair, the lower flange being wedge-like and insertible within the channel of the chair block.
2. In combination with the meeting ends 25 of rails, a chair upon which said meeting ends are adapted to rest, the opposite end portions of said chair being provided with upstanding blocks, the opposed faces of the blocks being provided with channels, the upper walls of said channels being longitudinally inclined, the inclination of one of said 30 upper walls being reversed to the inclination of the upper wall of the second channel, plates arranged at opposite sides of the meeting ends of the rails, each of said plates being provided with an outstanding block provided with a channel affording separated flanges, the upper flange of the block being adapted to overlie a block of the chair, the lower flange being wedge-like and insertible within the 35 channel of the block; and co-acting means carried by the upper flanges of the blocks of the plates and the blocks of the chair for holding said plates in applied position.
3. In combination with the meeting ends 40

of rails, a chair upon which said meeting ends are adapted to rest, the opposite end portions of said chair being provided with upstanding blocks, the opposed faces of the blocks being provided with channels, one 50 of the walls of each of said channels being inclined, the inclination of the wall of one of said channels being reversed to the inclination of the wall of the second channel, and plates arranged at opposite sides of the 55 meeting ends of the rails; each of said plates having an outstanding block provided with a channel affording separated flanges, the upper flange of said block being adapted to overlie a block of the chair, the lower flange 60 being wedge-like and insertible within the channel of the block.

4. In combination with the meeting ends 65 of rails, a chair upon which said meeting ends are adapted to rest, the opposite end portions of said chair being provided with upstanding blocks, the opposed faces of the blocks being provided with channels, one 70 of the walls of each of said channels being inclined, the inclination of the wall of one of said channels being reversed to the inclination of the wall of the second channel, plates arranged at opposite sides of the meeting ends of the rails, each of said plates having an outstanding block provided with a channel affording separated flanges, the upper flange of said block being adapted to overlie a block of the chair, the lower flange 75 being wedge-like and insertible within the channel of the block; and means disposed through the upper flange of each of the blocks of the plates and engageable with the adjacent block of the chair, for holding the plate in applied position.

In testimony whereof I hereunto affix my 85 signature in the presence of two witnesses.

GEORGE C. BOLES.

Witnesses:

G. W. BOULES,
JOHN H. STOGGS.
